UNITED STATES PATENT OFFICE

NELSON K. SMITH, OF LOS ANGELES, CALIFORNIA, ASSIGNOR TO BYRON JACKSON CO.,
OF LOS ANGELES, CALIFORNIA, A CORPORATION OF DELAWARE

ELEVATOR

Application filed December 7, 1929. Serial No. 412,479.

This invention relates to elevators of the type employed for raising and lowering well casing, pump tubing, and the like, in the operations of drilling a well and maintaining 5 the well in production after it is drilled.

This invention mainly relates to features of construction that are applicable to, so termed, double door elevators. In other respects the invention relates to a vertically 10 operating latch.

An important object of the invention is to prevent, by a comparatively simple construction, the doors getting out of alignment with one another which would make 15 it impossible for the doors to be closed about the casing until they were aligned.

Another object is to provide a vertically swinging latch whose center of gravity, when the latch is closed, is inwardly of a vertical 20 plane that passes through the axis of the latch pivot so that the weight of the latch tends to forcibly close it, if it has not been entirely closed by the operator when the elevator strikes the lower end of the collar or 25 coupling of the tubing or casing as said elevator is hoisted after being closed about the tubing or casing at some point below the level of said collar or coupling.

Another object is the provision of a latch 30 that operates in a vertical plane toward and from the vertical axis of the elevator.

Other objects and advantages will appear in the subjoined detailed description.

The accompanying drawings illustrate the 35 invention:

Fig. 1 is a plan view of an elevator constructed in accordance with the provisions of this invention, the doors being closed in 40 readiness for supporting a casing or other member that is to be lifted or lowered.

Fig. 2 is a front elevation of Fig. 1.

Fig. 3 is a vertical elevation from the irregular line indicated by 3—3 Fig. 1, a portion being in section on said line. The latch 45 is shown closed in full lines and in unlatched position in dotted lines.

Fig. 4 is a fragmental elevation, partly in section, from the line indicated by 4—4, 50 Fig. 1.

Fig. 5 is a fragmental horizontal section on the line indicated by 5—5, Fig. 2.

Fig. 6 is a rear elevation of Fig. 1, showing the back of the elevator.

Fig. 7 is a horizontal section on the line 55 indicated by 7—7, Fig. 6, the parts being in the positions they occupy when the doors are open.

Referring to the drawings, there is provided a pair of members or doors 11, each 60 of which is provided in its inner face with a semi-circular recess 12 which, together with the inner concave face 13 of a member 14 constitute the bore of the elevator. The doors 11 are connected by pivots 15 with the member 14 so that the doors can be swung into 65 open position for reception of the casing or other member that is to be supported by the elevator.

Each of the pivots 15 passes through upper and lower ears 16, 17, respectively, that project rearwardly and each of said pivots also passes through spaced upper and lower ears 18, 19 that project laterally from the member 14. The ears 18, 19 are disposed between the ears 16, 17, and the member 14 has a central portion 20 that projects upwardly above the level of the ears 18 between the rear end portions of the doors 11. The curved face 70 13 is the inner face of the portion 20. In this instance the pivots 15 are held in place by being threaded, as indicated at 21, into the ears 17 and the upper ends of the pins are provided with heads 22 which engage the upper faces of the ears 16.

The ears 17 practically meet in a plane that passes through the axis of the elevator bore and the adjacent faces of the ears 17 are convex so that said ears will not interfere with one another in the closing movement of the doors and so, at the same time, when the doors are closed the inner convex faces 221 of said ears 17 are contiguous. The ears 17 are provided with recesses 23 in their adjacent faces for the accommodation of a loose or floating bar 24, the purpose of which is to maintain the doors against becoming offset from one another as respects the axes of the pivots 15. By this construction, just described, for pivotally connecting the doors 75 80 85 90 95 100

11, I prevent the doors, when open, getting out of alignment with one another which would interfere with closing the doors about the pipe or casing. If the doors were to get 5 out of alignment it would be necessary to realign them before they could be closed about the tubing or casing.

In the Wilson patent, No. 1,468,589, there 10 is disclosed a trunnion construction for the elevator that will cooperate with the elevator bail links in a manner to avoid accidental closing of the elevator by gravity after said elevator has been opened and is being raised into position to be placed around another section 15 of casing or tubing. To obtain this same result, I provide a different construction of the trunnion as will now be described:

The trunnions are indicated at 25 and they 20 are in a plane that passes through the axis of the elevator bore. Each trunnion 25 is bifurcated or provided with a vertical slot 26 in which is pivotally mounted at 27 a suitable keeper 28 for preventing the elevator bail links, not shown, from becoming accidentally 25 detached from the elevator doors. The keepers 28, not being a portion of the present invention, need not be described in detail herein as keepers of this type are well understood in the art relating to oil well elevators.

Each of the vertical slots 26 divides the trunnion 25 into a pair of ears 29, 30, the 30 trunnion ears 29 being the front ones and the trunnion ears 30 being the rear ones. The bottom faces of the ears 29 are constructed 35 differently than the bottom faces of the ears 30, since the bottom faces of the front ears 29, as seen in Fig. 2 at 31, extend aslant downwardly and outwardly so as to tend to hold 40 the links of the elevator bail inwardly away from the keepers 28. The bottom faces 32 of the rear ears 30 are substantially horizontal so that when the elevator doors are open and the elevator tilts forwardly and 45 downwardly on the bail links, as is generally the case, the said links, which then stand oblique with reference to the trunnions, will not bind on the ears 30 in a manner to tend to force the doors out of their full open positions. Thus the slanting portions 31 of 50 the trunnions prevent the bail from straining against the keepers 28 while the horizontal faces 32 of the trunnions permit tilting of the open doors without such binding between the bail links and trunnions as would tend to close said doors.

The latch construction is as follows:

The doors 11 are provided, respectively, 55 with forwardly projecting lugs 33, 34 which, when the doors are closed, are juxtaposed as seen in Fig. 5. In this juxtaposed position the lugs 33, 34 are adapted to be embraced by a latch 35 which is provided with an opening or recess 36 to accommodate said lugs 33, 34. 60 The latch 35 is movably mounted so that it

can be withdrawn from the lugs 33, 34 and, in this instance, the mounting of the latch 35 is such as to provide for swinging or rocking of said latch toward and from the doors. To secure this swinging or rocking movement, 70 the latch is provided in its upper portion with a horizontally extending pivot 37 which, in this instance, takes the form of a bolt with the head on one side of the latch and the nut on the other side. The pivot 37 passes 75 through spaced ears 38 of the latch, the space between said ears constituting a slot or recess 39 to accommodate an ear 40 on one of the doors 11, the pivot 37 passing transversely through said ear 40. Thus the ears 38 embrace the ear 40. The axis of the pivot 37 lies in a vertical plane that parallels the axis of the elevator bore and, preferably, said plane lies outwardly from the lugs 33, 34. To secure this result the upper portion of the latch constitutes a horizontal leg 41 projecting from the vertical leg 42 of the latch, which vertical leg is provided with the recess 80 85 36.

The weight of the latch 35 is distributed 90 in such a manner with respect to its pivot 37 that the center of gravity of the latch, when the latch is closed, is inwardly of a vertical plane that passes through the axis of the latch pivot so that the weight of the latch tends to forcibly close it, if it has not been entirely closed by the operator when the elevator strikes the lower end of the collar or coupling of the tubing or casing as said elevator is hoisted after being closed about the tubing or casing at some point below the level of 95 said collar or coupling.

The latch is further insured against opening, when closed, by reason of the outer face 100 421 of the lug 34, which is the face that is adjacent to the latch, extending aslant inwardly toward the bore of the elevator. For the same reason the adjacent face 422 of the latch, preferably, is of a complementary slant.

The outer end of the latch leg 41 is provided with a downwardly extending handle 43 which is spaced from the latch leg 42 so that the fingers of the operator's hand can pass between the handle 43 and leg 42 to grasp said handle 43. In this instance, the handle 43 extends downwardly toward the leg 42. The handle 43 has an angular portion 44 at its upper end where it connects with the leg 41 so that that portion of the handle that is grasped by the operator is positioned approximately in alignment with the lugs 33, 34.

Each of the doors 11 is provided with a handle 45 and when the elevator is closed, the handles are approximately in alignment with the handle 43, as clearly shown in Fig. 5. Thus the several handles are conveniently positioned near one another and in the same plane so that convenience in opening and closing the elevator is insured. The handle 45 also extends aslant downwardly toward the 120 125 130

doors with which they are associated and are joined at their upper ends by legs 46 and at their lower ends by legs 47 with the elevator doors, thus leaving horizontally extending 5 openings 48 to accommodate portions of the hands of the operator when he grasps the handles 45.

Though gravity may be sufficient to maintain the latch 35 closed and to move said latch 10 into closed position from open position, it is preferable not to depend entirely upon gravity but to provide means for yieldingly urging the latch toward its latching position. For this purpose there is provided a coil 15 spring 49 which seats at one end within a recess 50 provided in the door on which the latch is mounted. The other end of the spring 49 seats on top of the leg 41 outwardly from the latch pivot 37, thus tending to force the 20 leg 42 inwardly toward the doors and in a plane that passes through the lugs 33, 34.

The construction and operation of the invention will be understood from the foregoing description, and, briefly stated, the operations 25 is as follows: Assuming that the elevator is closed, as illustrated in Fig. 1, that it is suspended from the elevator bail, not shown, and that it is desired to open the elevator preliminarily to engaging it around 30 a well casing, pump tubing, or the like, the operator, standing in front of the elevator, grasps the latch handle 43 and pulls it toward him, thus moving the latch recess 36 out of the vertical plane occupied by the lugs 33, 34. 35 While holding the latch open, the operator then grasps the handle 45 of that door on which the latch is not mounted and forces the door open to a sufficient extent so that he can release the latch without said latch 40 embracing the lug 34. He then releases the latch and grasps the handle 45 of the other door and pressing outwardly against both handles 45 simultaneously swings both doors into their wide open positions.

45 The elevator is then swung into a position to surround the tubing that is to be raised or lowered, in a manner well understood in this art, and the operator then grasps the door handles 45 and pulls them toward one 50 another so as to close the doors about the tubing. As the lug 34 and latch 35 come into a position, in the closing movement of the door, to engage, the lug 34 causes the latch to swing outwardly against the retracting 55 force of the latch spring so that the lug 34 will readily slide past the latch and into the recess 36 of said latch. In order to facilitate this, the outer corner of the lug 34 that is adjacent to the lug 33 is curved or 60 beveled, as indicated at 51 and, also, that portion of the latch 35 that, in the closing movement of the doors strikes the lug 34, is beveled inwardly and rearwardly, as indicated at 52.

65 Referring more particularly to Fig. 7, the

action of the floating bar 24 in maintaining the doors in registration will be readily understood for, assuming that the doors are being closed, if there should be a tendency 70 for the operation of the doors to cause offsetting of said doors with respect to one another, engagement of the floating bar 24 with the walls of the recesses 23 would prevent such displacement of either or both doors as would offset them. 75

I claim:

1. An elevator of the character described comprising doors provided in their inner faces with concave recesses, means pivotally connecting said doors at one end, a lug on the other end of each door, a latch mounted on one of the doors at a different level than the lugs and movable toward and from said doors and provided with a recess to receive the lugs when the doors are closed. 80

2. An elevator of the character described comprising doors provided in their inner faces with concave recesses, means pivotally connecting said doors at one end, a lug on the other end of each door, a latch pivotally 90 mounted on one of the doors at a different level than the lugs and movable toward and from said doors and provided with a recess to receive the lugs when the doors are closed. 95

3. An elevator of the character described comprising doors provided in their inner faces with concave recesses, means pivotally connecting said doors at one end, a lug projecting horizontally from the other end of each door, a latch mounted on one of the doors at a different level than the lugs and movable toward and from said doors and provided with a recess to receive the lugs when the doors are closed. 100

4. An elevator of the character described comprising doors provided in their inner faces with concave recesses, means pivotally connecting said doors at one end, a lug projecting horizontally from the other end of each door, a latch provided with a recess to receive the lugs when the doors are closed, and a horizontal pivot at a different level than the lugs connecting the latch with one of said doors, said pivot being at substantially 110 a right angle to a plane extending through the vertical axis of the elevator and midway between the doors. 115

5. An elevator of the character described comprising doors provided in their inner faces with concave recesses, means pivotally connecting said doors at one end, a lug projecting horizontally from the other end of each door, a latch provided with a horizontal leg and with a vertical leg and with a recess to receive the lugs when the doors are closed, and a horizontal pivot connecting the horizontal leg with one of the doors, the axis of said pivot lying in a vertical plane that lies outwardly from the lugs. 120 125

6. An elevator of the character described 125

comprising doors provided in their inner faces with concave recesses, means pivotally connecting said doors at one end, a lug on the other end of each door, a latch mounted 5 on one of the doors movable toward and from said doors and provided with a recess to receive the lugs when the doors are closed, one of the lugs having its outer face extending aslant inwardly toward the bore of the 10 elevator for engagement by the adjacent wall of the latch recess.

7. An elevator of the character described comprising doors provided in their inner faces with concave recesses, means pivotally 15 connecting said doors at one end, a lug on the other end of each door, a latch mounted on one of the doors movable toward and from said doors and provided with a recess to receive the lugs when the doors are closed, one 20 of the lugs having its outer face extending aslant inwardly toward the bore of the elevator for engagement by the adjacent wall of the latch recess and said adjacent wall of the latch recess provided with a complementary slant.

8. An elevator of the character described comprising doors provided in their inner faces with concave recesses, means pivotally connecting said doors at one end, and a latch 30 pivoted to the other end of one of the doors and engaging over cooperating means on the doors, the upper portion of the latch constituting a horizontal leg and the latch pivot extending horizontally through said leg, the 35

outer end of the leg provided with a downwardly extending handle.

9. An elevator of the character described, comprising two casing engaging jaws hingedly connected together, a lug on one of said jaws projecting outwardly therefrom and latch means mounted on the other jaw for engaging said lug when said jaws are in closed position, and a face on said latch contacting with a face on said lug to prevent opening of said jaws, the contact faces on said lug and latch being so shaped that separation of said jaws tends to force said latch further onto said lug.

10. An elevator of the type described, comprising two casing engaging jaws hingedly connected together at one end, a latch, hinge means securing said latch to one of said jaws, said latch moving into locking and releasing positions by rotation about said hinged means and having a contact surface which moves through an arc about said hinge during rotation of the latch, a lug on said other jaw having a surface engaging with the surface of said latch in locking position, the outer portion of said lug surface extending into the said path of said latch surface whereby opening force on said jaws locks said latch against rotation into its releasing position.

Signed at Los Angeles, California, this 25th day of November 1929.
